UNITED STATES PATENT OFFICE

124,159

DESIGN FOR A COMBINED CONTAINER AND SOAP DISPLAY

Harold B. Stoner, Dayton, Ohio, assigner to The Hewitt Soap Company, Inc., Dayton, Ohio, a corporation of Ohio

Application November 24, 1939, Serial No. 88,456

Term of patent 14 years

To all whom it may concern:

Be it known that I, Harold B. Stoner, a citizen of the United States and a resident of Dayton, in the county of Montgomery and State of Ohio, have invented a new, original, and ornamental Design for a Combined Container and Soap Display, of which the following is a specification, reference being had to the accompanying drawing, forming part thereof.

In the drawing:

I claim:

The ornamental design for a combined container and soap display, as shown and described.

HAROLD B. STONER.
